UNITED STATES PATENT OFFICE.

CHARLES LOMBARDO, OF WATERFORD, NEW JERSEY.

WINDOW-FASTENER.

1,302,687.

Specification of Letters Patent.

Patented May 6, 1919.

Application filed May 15, 1917. Serial No. 168,771.

To all whom it may concern:

Be it known that I, CHARLES LOMBARDO, a citizen of the United States, residing at Waterford, in the county of Camden, State 5 of New Jersey, have invented certain new and useful Improvements in Window-Fasteners; and I do hereby declare the following to be a full, clear, and exact description of the invention, such as will enable others 10 skilled in the art to which it appertains to make and use the same.

This invention relates to improvements in fastening devices for windows, and has for an object to provide a mechanism of simple, 15 novel and inexpensive construction by which the upper and lower sashes of a window may be readily and securely held in open, closed or various intermediate positions, and which furthermore is conveniently 20 manipulated to lock the sashes against movement or release the same so that they may be freely raised and lowered.

With the above and other objects of similar nature in view, the invention consists in 25 the construction, combination and arrangement of parts, set forth in and falling within the scope of the appended claims.

In the drawings:—

Figure 1 is a front elevation of a window 30 with the invention associated therewith,

Fig. 2 is a side elevation of the window frame and fastener, part being broken away,

Fig. 3 is a detail section taken on the line 3—3 of Fig. 2,

Fig. 4 is a detail section of one of the parts 35 and its related mechanism shown in their retracted or inactive position,

Fig. 5 is a view similar to Fig. 4 with the pawl in locked position, and

Fig. 6 is a fragmental view of the ratchet 40 plate which is secured to a rail of the window sash.

Referring now more particularly to the accompanying drawing, there is illustrated 45 conventionally a window including the usual frame or casing 10, and upper and lower sashes 11 and 12 respectively. Interposed between one of the pulley stiles 13 of the window casing and the adjacent side rail of 50 each of the sashes is a plate 14, the same being screwed to the sash and having therein a plurality of slots 15 the purpose of which will subsequently appear.

Midway of one side of the window casing 55 there is countersunk and secured a plate 16 provided with a pair of spaced bearing

openings 17 and arcuate series of apertures 18 concentric with the respective openings. Suitably secured to the above mentioned pulley stile 13 are two U-shaped brackets 19 60 in the legs of which are rotatably mounted a pair of parallel shafts 20. These shafts 20 have their outer ends extended through the bearing openings 17 in the plate 16 and have fixed thereon cranks 21 in the handles 65 of which spring pressed latches 22 are provided and adapted for selective engagement in the related series of apertures 18 to maintain the shafts in various positions of their rotation. At the other or free ends of the 70 shafts there are carried rocker arms 23 provided with slots 24, while secured also to the pulley stile 13 are plates 25 each having an aperture 26 through which and through said stile is operatively engaged a spring 75 pressed pawl 27 for co-operation with the slots in the corresponding plate 14.

In order to manipulate the pawls so that the sashes may as desired either be positively locked against movement, or permitted to move in one or both directions, there are carried by the pawls fixed lateral projections 28 which enter the slots of the adjacent rocker arms 23.

Thus when the cranks 21 are positioned 85 with their catches 22 engaged in certain of the apertures 18 the pawls 27 will be immovably held by the rocker arms 23 within the related slots in the plates 14 and the sashes will in consequence be securely locked 90 in their respective positions. Should it be desired to permit opening movement of the sashes but to prevent them being closed, the cranks 21 are moved to engage the catches in certain other of the apertures 18 at which 95 time the pawls 27 will be free to ratchet on the plate 14 as will be evident. Positioning of the catches in the remaining apertures serves to throw the pawl 27 entirely out of engagement with the plates 14 so that the 100 sashes may be moved at will in either direction.

What I claim is:—

1. A window fastener for sashes mounted in the usual frame with the upper portion 105 of the lower sash overlapping the lower portion of the upper sash when said sashes are closed; comprising a casing adapted to be fitted in the frame to overlie said overlapped portions, engaging members within the casing for disposition through the frame at the sash edges to simultaneously or inde-

- pendently engage the latter when closed or at any position of sliding movement of one with respect to the other to hold said sashes in adjusted relation, said engaging means comprising spring pressed bolts, the sashes having spaced sockets along the edges thereof for engagement by said bolts, shafts journaled in the casing and protruding through the frame, the inner ends of the shafts terminating adjacent the respective bolts, rocker arms on the inner ends of the shafts having inclined slots therethrough, fixed lateral projections on the bolts movably engaged through the slots whereby rotation of the shafts will serve to move the bolts into positive engagement with the sockets, out of engagement therewith or to intermediately withdraw said bolts to permit the same to ratchet in the sockets, and means on the shafts and outwardly of the frame to turn the shafts in either direction to oscillate the rocker arms and cause actuation of the bolts as stated or to hold the same in its particular actuated position.
- 25 2. A window fastener comprising a casing, a pair of angular bearings therein, horizontal parallel shafts journaled in the bearings with their inner ends protruding one beyond the other for disposition in different vertical planes, plate-like rocker arms fixed to said inner ends at right angles to the axes thereof, spring pressed bolts each having an inclosed casing forming a bearing, said bolts being disposed with their axes parallel

to the rocker arms and having fixed projections at right angles thereto, said rocker arms having slots engaged by said projections, a bearing plate through which said shafts extend and having arcuate series of apertures therethrough for each shaft, and cranks fixed to the shafts and having latches at the free ends thereof for selective engagement in the related series of apertures, as and for the purposes specified.

3. A window fastener comprising a shaft 45 for horizontal mounting in a window casing to project from the face thereof parallel to the edge of a sash movable in said casing, said edge having a series of spaced openings, a bolt disposed at right angles to the shaft 50 on a different horizontal plane for movement through the casing to engage said openings in the edge of the sash, a rocker arm fixed to the inner end of the shaft and having an elongated slot having movable 55 connection with the bolt to project or retract the latter upon oscillation of the rocker arm, a plate through which said shaft extends and having an arcuate series of apertures, a fixed crank on the shaft and a spring 60 pressed latch on the crank for engagement with the respective apertures.

In testimony whereof, I affix my signature in the presence of two witnesses.

CHARLES LOMBARDO.
